DESIGN FOR A TIME RECORDING MACHINE

George H. Kress, Vestal, N. Y., assignor to International Business Machines Corporation, New York, N. Y., a corporation of New York

Application March 30, 1948, Serial No. 145,452

Term of patent 14 years

(Cl. D64—10)

To all whom it may concern:

Be it known that I, George H. Kress, a citizen of the United States, residing at Vestal, in the county of Broome and State of New York, have invented a new, original, and ornamental Design for a Time Recording Machine, of which the following is a specification, reference being had to the accompanying drawing, forming part thereof.

Fig. 1 is a perspective view of a time recording machine, showing my new design.

Fig. 2 is a side elevation of the same.

Fig. 3 is a front elevation of the same.

I claim:

The ornamental design for a time recording machine, as shown.

GEORGE H. KRESS.
